UNITED STATES PATENT OFFICE

146,460

DESIGN FOR A SHUTTLECOCK

Fred Bentley, Lansing, Mich.

Application February 4, 1946, Serial No. 126,253

Term of patent 14 years

(Cl. D34—5)

To all whom it may concern:

Be it known that Fred Bentley, a citizen of the United States of America, residing at Lansing, in the county of Ingham and State of Michigan, have invented a new, original, and ornamental Design for a Shuttlecock, of which the following is a specification, reference being had to the accompanying drawing, forming a part thereof wherein:

Figure 1 is a side elevation of a shuttlecock, showing my new design.

Figure 2 is a top plan view.

Figure 3 is a sectional view taken on the line 3—3 of Figure 1.

I claim:

The ornamental design for a shuttlecock, as shown.

FRED BENTLEY.
